UNITED STATES PATENT OFFICE.

LESLIE H. L'HOLLIER, OF AKRON, OHIO, ASSIGNOR TO THE B. F. GOODRICH COMPANY, OF NEW YORK, N. Y., A CORPORATION OF NEW YORK.

FORM-FITTING BOOT.

Application filed February 6, 1926. Serial No. 88,602.

This invention relates to boots and especially to rubber boots, and its chief object is to provide a water-tight boot adapted to fit closely about the ankle and yet to be easily put on and removed.

Of the accompanying drawings:

Fig. 1 is a perspective view of a boot embodying my invention in its preferred form, as worn, a portion of the rubber cover being broken away.

Fig. 2 is a perspective view of the same, with the fastening device released, for putting on or taking off the boot.

Fig. 3 is an elevation of the boot as worn. Fig. 4 is a horizontal section of the boot, on line 4—4 of Fig. 1.

Referring to the drawings, the boot is formed with a comparatively slender ankle portion and the wall of the boot is formed with a slit 10 having closed ends and extending only from a point over the instep to a point just above the ankle.

Extending across the slit within the boot is a water-proof closure member 11 resembling a bellows tongue, the said member having its entire peripheral margin built into the wall of the boot throughout an annular zone extending around the slit 10 at a distance therefrom, the closure member 11 having such fullness as to permit the slit 10 to open widely and being adapted to lie against the ankle of the wearer in the folded condition shown in Fig. 4 when the slit is closed.

A slide fastener of the well known type shown is preferably employed for closing the slit 10, although my invention is not wholly limited thereto, and the jaw members 12, 12 of the fastener are preferably mounted upon anchorage strips 13, 13 of elastic fabric such as rubberized, bias-cut or knitted fabric, to provide comfort in conjunction with a close fit, the anchorage strips defining the slit 10 and being built into the wall of the boot at their outer margins and underlying the rubber cover 14 of the boot, as shown clearly in Fig. 4.

The slide fastener, when used, includes an actuating slide 15 and stops 16, 16 therefore mounted upon the respective anchorage strips 13 at the upper end of the slit 10.

The rubber cover 14 of the boot extends integrally over the entire surface of the boot, except at the slit 10, and as the slit is closed against the entrance of water by the bellows-

like closure member 11 the boot is water-tight throughout its height and is also form-fitting, and yet may be readily put on and taken off. Further advantages are neatness of appearance and comfort to the wearer, the close fitting ankle and elastic anchorage strips preventing the boot from sliding up and down excessively on the heel of the wearer. Another advantage, over a boot in which the vent and a fastening device therefor extend to the top of the boot, is that strains upon the fastening device are avoided, and a fastening device of the type shown may be closed throughout only a part of its extent, for comfort, without leaving the upper part of the leg portion open and without damaging the fastening device in use.

Modifications may be resorted to without departing from the scope of the invention as defined in the appended claims.

I claim:

1. A boot having a wall thereof formed with a slit having closed ends, a closure member for said slit joined about its entire periphery to the wall of the boot, and fastening means for joining and dis-joining the slit-defining margins, the said wall being of elastic construction in a region between the fastening means and the region of the closure member's attachment to the wall.

2. A boot as defined in claim 1 in which the closure member and the adjacent portions of the wall are of water-proof construction.

3. A boot having a wall thereof at the ankle portion formed with a slit having closed ends, means for joining and dis-joining the slit-defining margins of the wall, and a closure member underlying the slit and sealed to the wall of the boot throughout an annular zone circumscribing the slit, the said joining and dis-joining means comprising rows of interlocking jaw members mounted on the respective slit-defining margins and an actuating member slidably mounted on the two rows of jaws for joining and disjoining them, and the wall of the boot being of elastic construction in a zone defined by a line parallel and closely adjacent to the slit.

In witness whereof I have hereunto set my hand this 11th day of January, 1926.

LESLIE H. L'HOLLIER.
